WATCH FACE

Henry Du Pasquier, Neuchatel, Switzerland, assignor to Ernest Borel & Cie S. A., Neuchatel, Switzerland, a Swiss corporation

Application March 31, 1955, Serial No. 35,294

Term of patent 14 years

(Cl. D42—1)

FIG. 1.

FIG. 3.

FIG. 2.

FIG. 4.

FIG. 5.

Fig. 1 is a front view of a watch face, showing my new design, the design being formed by two relatively rotatable discs;

Figs. 2 and 3 are views similar to Fig. 1 but show the discs in different relative positions;

Fig. 4 is a front view of the upper disc, the unshaded portions being transparent; and

Fig. 5 is a front view of the opaque lower disc.

The design is embodied in the portions shown in solid lines.

I claim:

The ornamental design for a watch face, as shown and described.
